LOOM WITH SHUTTLE CHANGING AND
LOOM STOPPING MECHANISMRichard G. Turner, Worcester, Mass., assignor
to Crompton & Knowles Loom Works, Worcester,
Mass., a corporation of MassachusettsOriginal application March 6, 1935, Serial No.
9,645. Divided and this application December

12 Claims. (Cl. 139—232)

This is a division of my co-pending application
Serial No. 9,645 filed March 6, 1935.

This invention relates to improvements in
fancy or multishuttle box looms and it is the general
object of the invention to provide such a loom
which is capable of replacing certain of the weaving
shuttles when their weft supplies are
practically exhausted and to stop the loom when
the weaving supplies of certain other of the shuttles
are substantially exhausted.

In the weaving of certain fabrics which call
for several kinds of weft it frequently occurs
that two colors predominate while one or two
other colors are used infrequently for decorative
purposes. In such a loom there is less need for
automatic renewal of the running weft in the
infrequently used weaving shuttles than is the
case with those shuttles which are in more frequent
action. My present invention provides an
efficient and comparatively simple loom which
changes a part only of the running shuttles automatically
and stops the loom when exhaustion
approaches in the other shuttles, so that they
may be replenished by hand.

It is a further object of my present invention
to provide a single weft detector on the magazine
end of the loom to detect the condition of each
running shuttle when at that end of the loom.
By such a feeler I am able to keep any shuttle
in action as long as desired and am not restricted
to any definite or limited sequence as is the
case with certain multishuttle shuttle changing
looms heretofore proposed. The detector
gives the indication which initiates either shuttle
changing or loom stoppage, depending upon
which of the several shuttles is empty.

It is a further object of my present invention
to provide two separate loom controllers, one a
shuttle changer and the other loom stopping
mechanism, both of which are under control of
a single weft detector, together with a part moving
in timed relation with the box motion which
controls the shifting or drop boxes. The shuttle
changing controller may include selector mechanism
for the shuttle changing magazine to afford
a choice of changing operations, while the stopping
controller will have but one mode of operation,
with the same result, namely stopping whenever
the less frequently used shuttles are exhausted.
By this arrangement the single weft detector
initiates all of the changes which are to bring
about an alteration in loom operation either
changing or stopping, while the part moving
in timed relation with the box motion determines
which kind of alteration is to occur.

It is a further object of my invention to provide
a loom as already described wherein an indication
for a shuttle change can be stored and retained
during and after a period in which the loom
is stopped for hand replenishment of some
of the shuttles. In this way a very active shuttle
carrying a white weft, for instance, can indicate
exhaustion when at the magazine end of the
loom and then upon arriving at the drop box end
of the loom be moved out of action by a control
exerted through the pattern mechanism, whereupon
an infrequently active shuttle comes into
action and acts through the detector to stop the
loom. Upon resumption of weaving the shuttle
first to indicate will ultimately become active
again and will be replaced by a similar reserve
shuttle upon its arrival at the magazine end of
the loom, the indication for such a change having
been retained.

When the weft feeler is on the magazine end
it must be withdrawn at the time of exchanging
shuttles to prevent breakage and a repeated indication.
Since certain of the shuttles in my improved
loom do not coat with the shuttle changing
mechanism but are replenished by hand the
feeler will not be withdrawn in such instances
and in order to prevent a continued flow of current
through a detector circuit during loom stoppage
I arrange to box those shuttles which act to
stop the loom on the side opposite the feeler
when the loom is stopped. In this way an exhausted
loom stopping shuttle is out of contact with the
feeler to prevent burning of the latter,
and a repeated indication cannot be given.

It is another object of my present invention to
employ the shuttle changing and loom stopping
means together with a warp stop motion and so
time the parts that when the loom is stopped
because of approaching exhaustion the shuttle
needing replenishment will be at the drop box
side of the loom whereas when the loom is stopped
because of a warp fault it will come on the
intervening pick or beat of the loom when
the active shuttle is on the opposite or magazine
side of the loom. By this relation the weaver can
tell at a glance whether the loom was stopped by
weft or warp fault.

I am aware that it has been proposed heretofore
to use multibox looms with bobbin changing
attachments, but practical experience shows that
such looms are not entirely satisfactory in the
weaving of certain fabrics because of the fact
that the shuttle is not fully threaded on the first
pick after transfer, and also the thread end ex-
tending from the outgoing bobbin is likely to be
55

drawn back into the shed to form a double pick. That part of my present invention which relates to renewal of the weft employs shuttle changing mechanism which places in action a shuttle which is fully threaded and completely removes the trailing weft end with the old shuttle.

The warp stop motion is ordinarily capable of giving an indication of warp fault at any time including that period in the cycle of the loom when the weft detector gives its indication. Where the loom stopping control for both the warp stop motion and the detector is exercised through a single solenoid there is an opportunity for the warp stop motion to excite the solenoid at the time the feeler is detecting on a full bobbin and a false indication for weft stopping might therefore result with the shuttle boxed in the shifting boxes. It is a further object of my invention to prevent such improper stopping by interrupting the circuit of the warp stop motion so that it cannot give an indication to the common controlling solenoid at the time the weft detector is having its detecting action.

With these and other objects in view which will appear as the description proceeds, my invention resides in the combination and arrangement of parts hereinafter described and set forth in the claims.

In the accompanying drawings wherein a convenient embodiment of my invention is set forth,

Fig. 1 shows the forward part of one end of the loom having my invention applied thereto,

Fig. 2 is a view of a part of the opposite end of the loom showing four shifting shuttle boxes together with the box motion,

Fig. 3 is a plan taken in the direction of arrows 3—3, Fig. 2,

Fig. 15 is a detailed horizontal section on line 15—15 of Fig. 5.

In the drawings I have shown several known mechanisms which cooperate with themselves and other new parts to carry my invention into effect. These known parts comprise the multishuttle magazine, the shuttle changing boxes and their lifter motion, selector means to determine which type of reserve shuttle is to replace the empty shuttle, weft detector mechanism, loom stopping mechanism, and box motion parts together with a four-cell gang of shifting shuttle boxes at the side of the loom opposite the magazine. These parts will be described after which the manner in which they are associated with my present invention will be set forth.

Referring to the drawings, the loom frame 15 supports a reserve shuttle magazine M having

front and back stacks of reserve shuttles 16 and 17, respectively. The front stack of shuttles is supported in part by a lever 18 having a finger 19 to pass under the bottom front shuttle. A link 20 connects lever 18 with a second lever 21 pivoted to the magazine and operated by a rod 22 which extends down toward the lower part of the loom and has adjustably secured thereto a hook 23.

The back stack of shuttles rests on a floor 24 and a plunger 25 is arranged to move the bottom rear shuttle forwardly into the compartment C located under the bottom front reserve shuttle. This plunger 25 is moved by a lever 26 operatively connected to a second downwardly extending rod 27 having a hook 28. A spring 29 may be used to return the plunger to its rear position. The magazine may have other parts not shown herein but set forth more specifically in my United States Patents Nos. 2,054,171 and 2,054,172. It is sufficient for the purposes of the present invention to state that if rod 22 be depressed by mechanism to be described a front reserve shuttle will be released to fall into the space C and that when rod 27 is depressed the bottom rear reserve shuttle is moved forwardly into the compartment. Any shuttle arriving in the compartment is ready to be moved to the lay and into action.

The means for actuating the rods 22 and 27 may comprise a changing box lever 30 having a lifting ledge 31 and pivoted about a fixed stud 32. The forward end of this lever 30 is connected by means of a two-part yielding link 33 to an upwardly extending box rod 34 to support upper weaving box 35 normally in active position and lower auxiliary box 36 below the race and unoccupied.

A lifting lever 37 is also pivoted to stud 32 and is rocked by means of cam 42 so that the forward end thereof moves upwardly every second beat of the loom shortly after the active shuttle is boxed on the shifting shuttle box side of the loom. A dagger 38 is movably mounted on the lifter lever 37 and normally clears the ledge 31 when rising, but is movable under ledge 31 by either of two trips 39 and 40, see Fig. 5, so as to raise lever 30. The rear end of lever 30 is provided with a lug 41 which moves down whenever the latch 38 raises the forward end of lever 30 and this lug has engagement with one or the other of the hooks already described.

The selecting mechanism for determining which of the hooks is to become operatively related with the stud 41 comprises a selector lever 43 pivoted as at 44 to a bracket 45 secured to the stud 32 in fixed position. The upper end of this lever is arranged to guide the hooks so that the same move back and forth with the rocking of the lever 43. When the lower arm 46 of lever 43 is pulled to the left by a cable 47 moved by the shifting boxes the forward hook 23 is under the stud 41, but when the cord or cable 47 is slackened a coil spring 48 attached to the lever 43 rocks the latter so that the hook 23 moves forwardly and under the stud 41.

Rocking of the lever 43 is operative through a rod 49 to move a slide 50 on a guide rod 51 to vary the position of the trips 39 and 40 so that but one of them can be positioned at a time to throw the latch 38 toward the ledge 31. A solenoid 52 is mounted on lever 30 and has a core 53 connected to a rocking trip 54 movable in a vertical plane fixed with respect to lever 30. The parts are shown more clearly in Fig. 13, where the hub 55 of a carrier 50 is shown as mounted

for sliding movement on rods 51 carried by lever 30. The carrier supports the latches 39 and 40 and when moved by rod 48 places one or the other of the latches in vertical alignment with the trip. The solenoid acts to rock the latches so that the lower end of the latter will swing from the normal inactive position at the right over toward the edge to direct dog 38 into lifting relation with the lever 30. The carrier 50 is not limited to the two positions corresponding to the two stacks of reserve shuttles in the magazine, but is capable of additional sliding motion for a purpose to be described.

The detector mechanism in this instance is illustrated as a double prong electric feeler D, see Fig. 1, fastened to a lever 60 and pivoted as at 61 to a bracket 62 secured to and extending forwardly from the magazine frame. Lever 60 has a finger 63 which is connected to a tension spring 64 operative normally to hold the detector in rearward detecting position with a stop screw 65 adjustable to determine the correct position of the prongs 66 and 67 of the detector.

The prongs 66 and 67 are normally so placed that they enter the active shuttle which is in the upper box on alternate beats as the lay L moves forwardly with the active shuttle on the magazine side of the loom in box 35. The detectors may if desired move through a binder 68 mounted on the lay and not sharing the vertical motion of the boxes. The object in mounting the detector on a movable support is to permit the same to be moved forwardly at the time of shuttle change so that it will clear the incoming and outgoing shuttles.

At the opposite end of the loom provision is made for accommodating a series of weaving shuttles, four being set forth herein of which but one only will be active at a time. These cells are shown at 10, 11, 12 and 13 and accommodate shuttles CS' CS², SS' and SS², respectively. As contemplated at present each of these weaving shuttles will return to the same cell at the shifting shuttle box side of the loom and will ordinarily enter the upper cell 35 at the opposite side except on shuttle changing beats of the loom. These cells are mounted on a rod 75 which is connected as indicated in Fig. 2 to the lower end of a link 76 in any approved manner. The latter is adjustably connected to the forward end of a box lifter lever 77 pivoted as at 78 to an arm 79 movable about a fixed stud 80. Stud 78 therefore constitutes a floating pivot for the lever 77 and by combining various movements of lever 77 and arm 79 the link 76 is given four different positions.

Any well-known means may be used to accomplish this result, but I have shown herein a pair of links 81 and 82 which are connected at their upper ends, respectively, to lever 77 and arm 79. These links are connected at their lower ends to cranks 83 and 84, respectively, which move about stub shafts 85 and 86, respectively. These latter shafts are movable independently of each other by a force derived from the bottom shaft 87 and they are controlled as to the time of their operation by pattern mechanism not shown and also sliding teeth on mutilated gears. For further details of the box motion reference may be had to patent to Lundgren No. 1,679,616. By relations which are well understood the up and down motions of the two links 81 and 82 can be combined to give the shifting shuttle boxes any one of four positions.

75 The loom stopping mechanism is shown in Figs.

1 and 10 where it will be seen that the usual form of shipper handle 90 on shipper shaft 91 has the lower end thereof connected with a knock-off rod 92. The latter is attached to the upper end of an arm 93 pivoted as at 94 to a knock-off housing 5 95. A rocking actuator arm 96 is moved by a cam 97 on bottom shaft 87 to have a rising and falling motion on alternate beats of the loom to give a finger 98 thereof first a working and then a non-working stroke. Arm 96 may move about 10 a pivot 99 also carried by the housing 95.

A solenoid 100 located in the housing has a core 101 which is normally down and operatively connected to a transmitting link 102 pivoted as at 103 to the arm 93 and having the 15 left end thereof normally below the path of the finger 98 when the latter has a working stroke. Upon energization of the solenoid the core is raised to lift the link 102 so that the same lies in the path of the finger 98, and as cam 97 20 25 gives the arm 96 a working stroke, the link is given a longitudinal motion to rock arm 93 forwardly and act through rod 92 to move the shipper handle rearwardly or to the right in the position shown in Fig. 1 to stop the loom. 25 The mechanism for stopping the loom just described may be similar to that shown in patent to Payne No. 1,873,465.

An upright lever 105 pivoted to the loom frame carries a rod 106 which extends rearwardly to 30 have connection with a spring 107 that normally acts to hold said lever 105 rearwardly. A clip 108 adjustably mounted on the rod 106 is connected by means of a spring 109 to the stem 110 of a switch 111 to be closed when 35 the shipper handle is in driving position but open when the shipper handle is in stopping position.

Reference to Fig. 11 shows that the arm 96 is forked at its rear end, fork 116 cooperating 40 with the cam 115. The latter is adjustable angularly on the bottom shaft so that the loom can be stopped with the lay about in protection position when the active shuttle is on the magazine side of the loom or in box 35. 45

The several mechanisms just described of themselves form no part of my invention and may be operated and constructed in the usual manner.

As previously stated my present invention relates to means for replacing either of two of the weaving shuttles when exhausted and stopping the loom when one or the other of the two remaining shuttles is depleted. The controls to determine whether the shuttle changing 55 mechanism or the loom stopping mechanism shall operate are exercised primarily by the pattern mechanism acting in the present instance through the box motion.

By referring to Figs. 2, 3 and 4, the box motion shown therein is capable of giving four positions to the shifting shuttle boxes which are determined by the positions of links 81 and 82. Shuttles CS' and CS² are those which are to be changed or replaced by fresh shuttles, 65 while shuttles SS' and SS² effect loom stoppage. Whenever box 10 or 11 is opposite the race the rear link 81 will be in high position, link 82 being down when box 10 is in picking position and up when box 11 is in picking position. When 70 boxes 12 or 13 are to be aligned with the race the link 81 will be down as shown in Fig. 4, and link 82 will also be down when box 12 is active and up as shown in Fig. 4 when the lowest cell or box 73 is in picking position. A simple control can be 75

exercised because of the fact that link 81 is in one position whenever the upper two boxes are active and down when either of the lower two boxes is active.

5 The cable 47 which rocks the lever 43, see Fig. 1, extends from the shuttle changing to the shifting shuttle box side of the loom and is led upwardly as shown in Fig. 2 to have adjustable connection with a positioning lever 120. This lever 10 has a rear arm 121 with a roll 122 to be held against a rotatable cam 123 moving with the crank 83 by means of spring 48 acting through lever 43.

A disabling lever 124 has a forward arm provided with a roll 125 to coat with a cam 126 secured to arm 121. Lever 124 also has an eccentric follower 127 to be guided in angular adjusted position to coat with a second rotatable cam 128 moving with crank arm 83. Cam 123 20 has a high dwell 129 and a low dwell 130, while cam 128 has a high dwell 131 and a low dwell 132. Follower 127 can be adjusted to vary the position of lever 124 by means of nut 127a on screw 127b carried by the disabling lever, see Fig. 3.

25 When either of the upper two cells is to be active the link 81 will be raised and the cam 128 given such a position that roll 127 is on its low dwell, thereby permitting roll 125 to move away from the cam 126 by gravity. In this position 30 therefore roll 122 and the positioning lever can respond to cam 123, being on the low dwell 130 when the boxes are in their lowest position and on the high dwell 129 when shuttle box 71 is in picking position. With link 81 raised therefore the 35 lever 43 can have the same character of selecting motions as have been heretofore described in my United States Patent No. 2,054,171 and 2,054,173.

40 From the description it will be seen that whenever the shifting is confined to boxes 70 or 71 the carrier 56 will slide to place one or the other of the latches 39 or 40 under the trip 54 and the loom will operate as a two-color shuttle changing loom, the shuttle changing mechanism being 45 in timed relation with the active shuttle CS' or CS², as the case may be.

When either of the lower shuttle boxes 72 and 50 73 is to be active, however, link 81 is down in the position shown in Fig. 4 and cam 128 takes such a position as a result of the reversal of crank arm 83 as to place follower 127 on the high dwell 131. This causes roll 125 to push cam 126 and the positioning lever to the third or neutral position shown in Fig. 4. This additional movement 55 of the positioning lever gives an increased motion to cable 47 and a corresponding shift to the lever 43.

The hooks 23 and 28 will occupy one of two positions when either of the upper pair of shuttle boxes is in picking position and these hooks together with the control lever 43 will under those conditions operate as in my aforesaid Patent No. 2,054,173. When the lever 43 is given its additional motion incident to the activity of 60 shuttle SS' or SS² provision must be made to prevent damage to the hook. This result I accomplish by means illustrated in Figs. 5, 6 and 7. Hook 23 will ordinarily pass through a hole 133 in the lever 43, see Fig. 15, and will therefore be 65 positively positioned by the latter when said lever rocks in either direction. Hook 28, on the other hand, lies in a slot 134 which is open at the front end thereof to receive a pressing finger 135. The latter is pivoted at 136 to lever 43 and a tension 70 spring 137 interposed between lever 43 and the

pressing finger holds the latter yieldingly in rear position to cause seating of hook 28 against the rear of slot 134.

The connections are such that when either of the upper two shuttle boxes is active the hooks 5 will move back and forth as previously described so that one or the other of them will be in operative relation with respect to the stud 41, but when the lever 43 is given its additional motion due to the activity of either shuttle SS' or SS², 10 the lever 43 will rock from the position shown in Fig. 6 to that shown in Fig. 7 and the yielding finger 135 will move forwardly relatively to the lever 43, holding the hook 28 against the pin 41. In this way the hooks are able to accommodate 15 the third position of the lever 43.

As will be apparent from Figs. 2 and 4 the positioning lever 120 maintains its third position due to the fact that link 81 is down and roll 122 20 is away from cam 123. The link 82 can therefore rise and fall to render either of the lower pair of shuttles active without disturbing the position of the disabling or positioning levers.

The control circuit has two branches, one of which goes to the shuttle changing solenoid 52, 25 and the other of which goes to the stopping solenoid 100. In order to determine which branch of the circuits and therefore which of the solenoids 52 or 100 shall be energized I provide a controller positioned by lever 43.

30 This controller comprises a box 140 carried by the fixed bracket 45 and having pivoted thereto as at 141 two circuit closing arms 142 and 143 carrying rolls 144 and 145, respectively, to contact with rocking cams 146 and 147, respectively. 35 Each cam has a high dwell 148 and a low dwell 149, but the dwells are staggered as shown in Fig. 5 so that when a high dwell of one cam is elevating its corresponding roll the low dwell of the other cam permits its roll to assume low 40 position. The two cams are rigid with a depending arm 150 connected by an adjustable rod 151 to the rocking control lever 43. The connection between rod 151 and the lever may include stud 152 adjustable along a slot 153 in 45 lever 43. By means of this adjustment the proper throw of the cams 146 and 147 may be derived from the lever 43.

46 As seen in Fig. 8 the arm 142 carries a contact screw 154 while the other lever 143 carries 50 a similar contact screw 155. These contacts are connected to wires 156 and 157, respectively, and are each adapted for engagement with a contact plate 158 insulated from and supported by the housing 140. A wire 159 is connected to the 55 contact plate 158 and depending upon the position of arm 150 one or the other of the contacts 154 and 155 will be in electrical engagement with the plate 158. The relation of the parts is such, however, that but one contact can be made with 60 the plate 158 at a time.

When the parts are in the position shown in Fig. 6 and the loom is set to exchange one or the other of the shuttles CS' or CS² contact 155 will be elevated by cam 147 while contact 154 65 will be down and touch plate 158. The dwell 148 of the cam 147 is sufficient to maintain this position whether box 70 or 71 is in picking position.

When either of the shuttles SS' or SS² is in 70 action the parts will take the position shown in Fig. 7, where it will be seen that contact 154 is raised by cam 146 and contact 155 is down on plate 158. It will be seen therefore that the box motion shown in Fig. 2 not only selects which of two shuttles CS' or CS² shall be replaced by 75

reserve shuttles, but also determines whether wire 156 and 157 shall be connected to plate 158.

It is customary in those types of looms which are supplied with shuttle changing mechanisms to employ an electrical warp stop motion. As already stated a warp stop motion is ordinarily always capable of giving its indication and might therefore excite solenoid 100 at the instant of contact between the detector and a full shuttle should a warp thread break at that time. There would result a misindication, which I prevent by interrupting the warp stop motion circuit periodically and during the interval that the weft detector is in contact with the weft supply being detected.

Referring to Fig. 10, I have shown the loom frame 15 as provided with a bracket 160 on the upper end of which is located a housing 161 supporting two insulated spaced contacts 162 and 163. These contacts may be of resilient material and are mounted as set forth particularly in Fig. 12 to be in vertical alignment with a contact closer 164. The closer is vertically adjustable on a block 165 sliding between the blocks 166 of insulating material on which the contacts 162 and 163 are mounted. The block derives its vertical reciprocating motion from a lever 167 pivoted as at 168 to the bracket 160 and having a roll 169 which contacts with a cam or eccentric 170 on the bottom shaft 87.

It is to be understood that in the normal operation of the loom the active shuttle will be on the magazine side every other beat of the lay, and since the bottom shaft has a complete revolution every other beat of the lay, the cam or eccentric 170 will act to raise lever 167 once for every alternate non-detecting beat of the lay and will act to lower the block 165 on the intervening detecting beats of the lay. The low point of the cam or eccentric 170 is so set as to effect lowering of block 165 during the detecting interval when the feeler is in contact with the active shuttle and the latter is on the magazine side of the loom. At other times the contact closer 164 is raised to complete a circuit between wires 171 and 172 which are connected, respectively, to the contacts 162 and 163. A pin and slot connection designated generally at 173 may be employed to effect reciprocation of the block 165 as the lever 167 rises and falls.

The bottom shaft 87 has secured thereto a cam 175 which is positioned for cooperation with a fork 176 formed integral with the arm 96. The latter may therefore be raised either by cam 97 for the normal warp stop operation of the loom, or by cam 175 at a different point in the cycle of loom operations and responsive to the weft detector. As seen in Fig. 10 the high points of these two cams are separated by a considerable angle and it is for this reason that the rod 92 can be acted upon to stop the loom by a warp fault with the shuttle on the magazine side of the loom or by a weft indication through cam 175 when the depleted shuttle SS' or SS² is on the shifting shuttle box side of the loom.

The warp stop motion is not shown structurally in the drawings but the essential parts thereof are indicated diagrammatically in Fig. 9, where it will be seen that a contact electrode 185 is inclosed by but insulated from a second contact electrode 186. The latter is connected by wire 187 to the ground and both contacts extend through a slot in the upper part of a drop wire 188 which is normally held elevated by the warp 75 W. Upon warp fault the drop wire falls to effect

electrical connection between the bars 185 and 186. For a further understanding of the structure and operation of the warp stop motion reference may be had to prior patent to Payne No. 1,852,024.

The operation of the several parts may be understood from the diagrammatic layout of the various circuits shown in Fig. 9. It will be understood that the pattern mechanism not shown controls the box motion so that one or another of the shuttle boxes may be opposite the race on the lay L. Assuming that either of the shuttles CS' or CS² is active, the contact 154 will rest on contact plate 158 and current will flow through the following circuit when uncovered 15 ferrule F of a bobbin B in the active shuttle is presented to the detector: ground, wire 182, the detector prong 67, ferrule F, prong 66, wire 159, plate 158, contact 154, (contact 155 being raised), wire 156, shuttle changing solenoid 52, wire 180, 20 binding post 190 of the switch 111, closure 189 of the switch, binding post 191 of the switch, wire 183, source of electric power P, and wire 184 to the ground. Current flowing in this circuit will energize the solenoid 52 to throw the 25 latch 39 or 40 corresponding to the indicating shuttle preparatory to an operation of the shuttle changing mechanism. So long as either of shuttles CS' or CS² is in action the contact 154 will be on plate 158 and if either of these shuttles 30 should present a depleted bobbin to the detector the circuit just traced will be closed and an indication will be given through the selector mechanism shown in Figs. 13 and 14. The slide of the selector which is positioned by the rod 49 will 35 be either in the dotted or full line position shown in Fig. 14 when the circuit already traced is closed. The relative position of the several parts associated with lever 43 will be in the position shown in Fig. 6, where the showing in full lines is for shuttle CS² and in dotted lines for shuttle CS'.

When the pattern mechanism calls for a change so that one of the shuttles SS' or SS² is to be active there will be a reversal of the contacts contained in the box 140 and upon presentation of an exhausted shuttle to the detector the following circuit will be closed: ground, wire 182, the weft detector, wire 159, plate 158, contact 155, (contact 154 now being up), wire 157, solenoid 100 of the knock-off device, wire 181, switch 111, wire 183, source of electric power P, and wire 184 back to the ground. Current flowing in this circuit does not energize the shuttle changing solenoid but does excite the solenoid 100 which controls the link 102. At a later time in the operation of the loom this link will be actuated as already described to stop the loom with the shuttle on the drop box side. During the closure of the second circuit the parts will be in the position shown in Fig. 7, and the carrier will be in the dot and dash position of Fig. 14, the structure being modified to permit the extra motion where the latches are out of possible engaging position with the dog 38.

It is to be understood that at the time the detector can close either of the two preceding circuits, the circuit closure 164 will be spaced from the contacts 162 and 163, and operation of the warp stop control will be temporarily prevented.

If a warp fault should occur at any time when the contacts 162 and 163 are connected, that is, at some time other than the detecting interval, the following circuit will be closed: ground, wire 187, bar 186, drop wire 188, bar 185, wire 171, con-

tact 162, circuit closure 164, contact 163, wire 172, solenoid 100 of the knock-off device, wire 181, switch 111, wire 183, source of electric power P, and wire 184 back to the ground. Current flowing in this circuit will set the knock-off device to stop the loom with the active shuttle on the magazine side of the loom.

It is to be understood that switch 111 is in the position shown in Fig. 9 so long as the loom is 10 running but when the shipper handle moves to stopping position spring 107 acts to permit opening of switch 111 so that whether the loom be stopped by the warp stop motion or the detector, current will not flow through their respective 15 circuits after the loom has come to rest.

From the foregoing it will be seen that I have provided a loom operating with a plurality of shuttles certain of which are replaced by a shuttle changing mechanism and others of which 20 effect loom stoppage upon depletion and that a single detector cooperates with all the weaving shuttles. It will further be seen that provision is made for stopping the loom with an active depleted shuttle in the shifting shuttle boxes, there- 25 by giving the weaver a visual indication as to the cause of loom stoppage. It will also be seen that I have provided a warp stop motion effective to stop the loom upon warp fault when the active shuttle is on the magazine side of the 30 loom. In this connection it should be noted that three conditions exist in the loom, namely, a depleted weaving shuttle of one group will effect stopping of the loom upon arrival at the shifting shuttle boxes, a depleted shuttle of another group will be replaced at the magazine side 35 while the loom continues to run, and the loom will come to rest with an active shuttle on the magazine side upon occurrence of a warp fault. Furthermore, it will be noted that the warp stop 40 motion is so controlled that it cannot act through the knock-off device during the weft detecting interval, provision thereby being made to prevent the warp stop motion from effecting loom stoppage should either of shuttles SS' or SS² present 45 a full supply of weft to the detector. Another feature of the invention is the provision of means actuated through a pattern mechanism controlled device, such as a box motion, to determine which of two circuits can be closed by the weft detector to effect either shuttle replacement 50 or loom stoppage. The hooks which coact with the shuttle changing mechanism are modified with respect to their previous arrangement so as to permit movement of the control parts to a third or neutral position when either shuttle SS' or SS² is active. The cams 97 and 175 are 55 so disposed angularly with respect to the bottom shaft 81 that they give the knock-off device two working strokes for each two pick cycle of the loom, one cam to assist stoppage effected by the weft detector and the other acting in conjunction 60 with the warp stop motion. Furthermore, the selector mechanism for the shuttle changer shown more particularly in Figs. 12 and 14 has provision for no additional motion beyond that heretofore employed to permit the latches to 65 move out of possible operative relation with respect to the dog which causes rising of the shuttle changing boxes at the magazine end of the loom. In connection with the selector mechanism it should be noted that either of shuttles CS' or CS² can give an indication of weft ex- 70 haustion while on the magazine side of the loom and then become inactive for a period during 75 which either of shuttles SS' or SS² is active with-

out loss of the indication, the return of the indicating shuttle to action immediately effecting a shuttle changing operation of the magazine without the necessity of a repeated indication. When the shuttles SS' or SS² become active the latches 5 are moved out of register with the dog so that had either latch been set by one of the shuttles CS' or CS² no premature indication of the magazine could result.

Having thus described my invention it will be 10 seen that changes and modifications may be made therein by those skilled in the art without departing from the spirit and scope of the invention and I do not wish to be limited to the details herein disclosed, but what I claim is: 15

1. In a loom having a plurality of shifting shuttle boxes, a box motion to move any one of the boxes to active position, a multi-color shuttle changing mechanism, a cam movable by the box motion, a selector for the shuttle changer 20 controlled by the cam when certain of the shuttle boxes are active, and a second cam movable by the box motion to interrupt control between the first cam and the selector when certain other 25 of the shuttle boxes are active.

2. In a loom having a plurality of shuttle boxes, a lever connected to said shuttle boxes, a pair of actuators for the lever, a cam moving with each actuator, a multicolor shuttle changing mechanism, a selector for the shuttle changing mech- 30 anism controlled by one of said cams and movable thereby to any one of a plurality of positions less than the number of shuttle boxes when certain of said shuttle boxes are active, and means actuated by the other cam to move said 35 selector out of control of the first cam when certain other of the shuttle boxes are active.

3. In a loom having a plurality of shifting shuttle boxes, a multi-color shuttle changing mechanism, a pair of actuators for the box lever, a cam 40 moving with each actuator, each cam having a high and a low dwell, a selector for the shuttle changing mechanism controlled by one of said cams when the shuttle boxes controlled by the corresponding actuator are active, and means op- 45 erated by the other cam to move the selector out of control of the first cam when other of the shuttle boxes are active.

4. In a loom having a plurality of shifting shuttle boxes, a box motion including a lever cap- 50 able of moving any box to active position, a pair of independently movable actuators for the lever, movement of the lever by one of the actuators rendering certain of the shuttle boxes active and movement of the lever by the other actuator mak- 55 ing certain other of the shuttle boxes active, a cam connected to each actuator and moving therewith, a multicolor shuttle changing mechanism, a selector for the shuttle changing mechanism controlled by one of the cams when the ac- 60 tuator corresponding thereto moves the lever to position certain of the shuttle boxes actively, and means moved by the other cam when the other actuator corresponding thereto moves the lever to render certain other of the shuttle boxes ac- 65 tive, said means moving the selector out of control of the first cam.

5. In a loom having a plurality of shifting shuttle boxes, a box lever connected to the shuttle boxes capable of moving any shuttle box to active position, a pair of actuators movable inde- 70 pendently of each other and each capable of causing motion of the lever, one of said actuators capable of moving the lever to two different po- 75 sitions, and the other actuator capable of mov-

ing the lever to two other positions, a cam connected to and moving with each actuator, a multicolor shuttle changing mechanism, a selector for the shuttle changing mechanism controlled by one of the cams, and means moved by the other cam to move said selector out of control of the first cam.

6. In a loom having a plurality of shifting shuttle boxes, a lever connected to the boxes and capable of moving any box to active position, a multicolor shuttle changing mechanism, two actuators for the lever, each actuator capable of giving the lever two different positions and the actuators together capable of giving the lever four different positions, a selector for the shuttle changing mechanism, means moving with one of said actuators to control and move the selector to either of two positions, and other means moving with the other actuator to move the selector out of control of the first means, the first means moving the selector when certain of the shuttle boxes are active and the second means moving the selector out of control of the first means when other of the shuttle boxes are active.

7. In a loom having a plurality of shifting shuttle boxes, a box shifting lever capable of moving any shuttle box to active position, a pair of actuators for the lever, each actuator capable of moving the lever to two positions, multi-color shuttle changing mechanism, a selector for the shuttle changing mechanism, and two cooperating levers one of which is connected to and capable of moving the selector mechanism, means moving with one of the actuators to move one of the levers and cause motion of the selector, and means moving with the other actuator to cause the other lever to move said one lever out of control of the first means when certain of the shuttle boxes are active.

8. In a loom having a plurality of shifting shuttle boxes, a box lever capable of moving any shuttle box to active position, a pair of actuators for the lever, a multicolor shuttle changing mechanism, a selector for the shuttle changing mechanism, cooperating levers one of which is connected to and capable of moving the selector, each cam having a high and a low dwell, one of said cams to move said one of the levers while the other lever is on one of the dwells of the other cam when certain of the shuttle boxes are active, said other cam to move said other lever when the latter moves to the other dwell of said other cam to move the first lever out of control of the first cam when certain other of the shuttle boxes are active.

9. In a loom operating with a plurality of shuttle boxes any one of which may become active, a multicolor shuttle changing mechanism to supply a plurality of types of reserve shuttles less in number than the number of shuttle boxes, a shuttle box motion having two independently movable actuators to move any shuttle box to active position, selector mechanism for the shuttle changing mechanism movable to a plurality of control positions with respect to the shuttle changing mechanism, means to connect one of the actuators to the selector mechanism to move the latter to a plurality of positions, indicating elements carried by the selector mechanism to control the shuttle changing mechanism, one element for each position of said one actuator,

said elements movable from non-indicating to indicating position, connections from the second actuator to the selector mechanism to give said actuator additional motion to move the elements out of control of the shuttle changing mechanism when certain of the shuttle boxes are active, and means to return the selector to the control of the first actuator after control of said selector by the second actuator is relinquished.

10. In a loom operating with a plurality of shuttle boxes any one of which may become active, said boxes cooperating with a plurality of weaving shuttles, a weft detector to detect the condition of weft in any active weaving shuttle, a shuttle changing mechanism to replace certain of said weaving shuttles in the shuttle boxes, connections between the detector and the shuttle changer to cause the latter to replace any one of a given number of weaving shuttles less than the total number of weaving shuttles in said shuttle boxes when indicating weft exhaustion through the detector, loom stopping mechanism, and connections between the detector and said stopping mechanism to render the latter effective to stop the loom when the detector indicates exhaustion of weft in the other weaving shuttles which are not replaced by the shuttle changing mechanism.

11. In a loom having a plurality of shifting shuttle boxes cooperating with a plurality of distinctive weaving shuttles, multicolor shuttle changing mechanism to supply reserve shuttles corresponding to certain of the weaving shuttles only, loom stopping mechanism, a weft detector to detect the condition of weft in any active weaving shuttle, connections between the detector and the shuttle changing mechanism to cause the latter to replace any of said certain weaving shuttles when depleted, and other connections between the detector and the stopping mechanism to cause the latter to stop the loom when the shuttles other than those replaceable by the shuttle changing mechanism indicate exhaustion.

12. In a shuttle changing loom having a plurality of shifting shuttle boxes any one of which may become active and operating with a plurality of distinctive weaving shuttles, a weft detector to determine the condition of and indicate exhaustion of weft in each weaving shuttle, a box motion to move any active shuttle box to active position, loom stopping mechanism, a multi-color shuttle changing mechanism to replace certain of the weaving shuttles, selector mechanism for the shuttle changing mechanism to determine the type of reserve shuttle to be supplied thereby, distributor means connected to the detector and operated by the shuttle box motion, a control from the distributor means to the stopping mechanism, and a second control from the distributor means to the selector, all indications of exhaustion given by the weft detector being communicated through the distributor means, the latter when in certain positions effecting loom stoppage by the first control means when certain of the weaving shuttle boxes are active, and the distributor means when moved to different positions by the shuttle boxes communicating the indication of the weft detector through the second control means to the selector when other shuttle boxes are active.
